PAVING MACHINE

Frederick J. Silbernagel, Huron, S. Dak., assignor to
Precision Paving Products, Inc., Minneapolis, Minn.

Filed Feb. 25, 1974, Ser. No. 445,642

Term of patent 14 years

Int. Cl. D15—04

U.S. Cl. D40—5

FIG. 2

FIG. 3

FIG. 3

FIG. 4

FIG. 5

FIG. 6

FIG. 7

FIG. 1 is a top plan view of a paving machine embodying my new design;

FIG. 2 is a side elevational view thereof;

FIG. 3 is a side elevational view thereof opposite to that shown in FIG. 2;

FIG. 4 is a front elevational view thereof;

FIG. 5 is a rear elevational view thereof;

FIG. 6 is a side elevational view thereof in an alternate position; and

FIG. 7 is a front elevational view thereof in the position of FIG. 6.

I claim:

The ornamental design for a paving machine, substantially as shown.
